USE OF EMULSIONS IN DEWAXING OIL

Robert A. Macke, Baytown, and Winfred O. Milligan, Houston, Tex., assignors, by mesne assignments, to Esso Research and Engineering Company, Elizabeth, N. J., a corporation of Delaware

Application September 8, 1952, Serial No. 308,325

4 Claims. (Cl. 196—18)

The present invention is directed to a method for solvent dewaxing lubricating oil.

It is well known to the art to remove wax from a waxy oil by dissolving the waxy oil in solvent, chilling the resultant solution to cause the wax to precipitate and then separating the precipitated wax by some suitable means such as filtration or gravity settling. The present application is directed to an improved method for solvent dewaxing oil.

The practice of the present invention will now be described in detail in conjunction with the accompanying drawing in which:

The sole figure is in the form of a flow sheet.

In the practice of the present invention an emulsion of the water-in-oil type is formed in which the water is dispersed to such an extent that at least 90% is within the particle size range of 5 to 20 microns.

Warm waxy oil is dissolved in solvent at a temperature above the wax nucleation temperature and emulsion is then incorporated therein in such an amount that the finely dispersed water droplets are present in the waxy oil in an amount within the range of .25 to 5% by volume. The resultant solution containing the finely dispersed water droplets is then cooled to the desired dewaxing temperature which causes the separation of wax particles in the form of large agglomerates thereby allowing the ready separation of the wax phase from a wax free oil phase.

The important features of the procedure are the forming of a separate water-in-oil type of emulsion which is incorporated in the solution of waxy oil dissolved in solvent at a temperature above the wax nucleation temperature under such conditions that the finely dispersed water particles pass into the waxy oil and remain therein while the waxy oil is chilled to a temperature below the wax nucleation temperature. As stated heretofore, in the practice of the present invention the finely dispersed water present in the waxy oil at the wax nucleation temperature may be within the range of .25 to 5% by volume and satisfactory results will be obtained. With a lubricating oil feed stock containing wax within the range of 5 to 25% by volume it will often be found that when the free water at the wax nucleation temperature is within the range of .25 to 1.10% by volume the most satisfactory results are secured. It may be found when separating oil from wax mixtures where the wax is present in considerably greater amounts, for example over 50%, that larger amounts of water in finely dispersed form, up to 5% by volume at the wax nucleation temperature may give the most desirable results.

It is essential that the water added in the form of a water-in-oil type emulsion remain as finely divided particles dispersed in the waxy oil solution as the solution is chilled to below the wax nucleation temperature. Thus a solvent must be employed which will not cause the finely divided particles to coalesce before such a chilling can be carried out. It will usually be found desirable to

2

employ a solvent which has a low solubility for water. A preferred solvent is propane. However, the invention is not limited to propane since other solvents having a low solubility for water are well known to the art. Examples of other suitable solvents known to the art to have a low solubility for water are naphtha, high molecular weight alcohols such as amyl alcohol, a ketone-light aromatic hydrocarbon mixture, and chlorinated solvents such as ethylene dichloride benzol mixture, ethylene dichloride, carbon tetrachloride mixture and trichloroethylene. It may be possible to employ solvents or solvent mixtures having considerable water solubility by first saturating them with water but ordinarily this is not desirable. In general, if the solvent is capable of dissolving a considerable amount of water it will be preferable to dissolve the water in the solvent at a high temperature and then cool down to separate out the water in finely divided form as disclosed and claimed in the copending U. S. Patent application Serial No. 308,323, entitled "Solvent Dewaxing of Lubricating Oil" filed in the name of Robert A. Macke on September 8, 1952, while the present invention where finely divided water particles are obtained in the waxy oil solution by adding an emulsion thereto is particularly advantageous in cases where the solvent has a low water solubility.

Turning now specifically to the drawing which is in the form of a flow sheet, water from 10 and solvent from 11 are mixed together with oil from 15 introduced by valve-controlled line 9 to form an emulsion in emulsifier 12. Warm dewaxing solvent from 14 is used to dissolve warm waxy oil from 15, the two fractions being mixed in incorporator 16 to form a solution. The resultant solution has incorporated therein in incorporator 17 emulsion from emulsifier 12. The resultant solution of waxy oil has therein dispersed water particles in an amount within the range of .25 to 5% by volume with approximately 90% in the size range of 5 to 20 microns and is then chilled in 18 to a selected dewaxing temperature. It is to be emphasized that in the chilling step the finely divided water particles must be present as the waxy oil is chilled down through the wax nucleation temperature. The procedure followed causes the separation of wax particles in the form of agglomerates which are readily separated. The solution which has been chilled to the dewaxing temperature is then separated in separation step 19, such as filtering by means of rotary filter to obtain as products a dewaxed oil fraction and a wax fraction. The drawing is in the form of a flow sheet and it will be understood that various well known steps such as the recovery of solvent from the dewaxed oil and the separated wax have been omitted for the purpose of simplifying the description.

The present invention will be further described by way of the following example:

Example

A very tight emulsion was formed by admixing 82 parts by volume of water, 18 parts by volume of methyl ethyl ketone and 300 parts by volume of oil in a Waring blender for 30 seconds. A waxy distillate motor oil having a viscosity of 53.2 Saybolt seconds at 210° F. was divided into first, second and third samples. The wax nucleation temperature of the motor oil was approximately 115° F. To 100 parts by volume of each of the samples there was added 100 parts of a solvent mixture consisting of a 68% by volume of methyl ethyl ketone, 32% by volume of toluol solvent mixture containing 0.55% by volume of water at a temperature above the wax nucleation temperature so that each of the samples was dissolved in solvent mixture. No emulsion was added to the first sample. Emulsion was added in the

amount of 3.1% by volume to the second sample and an amount of 6.2% by volume in the third sample. Each of the samples was then chilled to approximately 0° F. and filtered. The first sample gave a dewaxed oil filter rate of 11.6 gallons per square foot per hour, the second sample gave a dewaxed oil filter rate of 14.2 gallons per square foot per hour or an increase of 22% over the first sample. The third sample gave a dewaxed oil filter rate of 12.8 gallons per square foot per hour or an increase of 10%. These results are tabulated in Table I set out hereafter. The first run where no emulsion was added produced a wax cake having 27% by volume of oil in wax, the second run produced a wax cake having 32% oil in wax, an increase by volume in oil, while the third run produced a wax cake having 24% by volume of oil in wax or a decrease of 11%.

Table I

Solvent Composition:
68% by volume methyl ethyl ketone
32% by volume toluol
0.55% by volume water added

Percent Emulsion added ¹	0	3.1	6.2
Percent Free water present in the waxy oil solution at nucleation temperature	0	0.64	1.28
Dewaxed Oil filter rate, gals./sq.ft./hr.	11.6	14.2	12.8
Percent Oil in wax	27	32	24
Percent Increase in filter rate		22	10

¹ 82 parts water; 18 parts methyl ethyl ketone; 300 parts oil.

It is not understood why the procedure of the present invention causes the substantial improvement in results which are obtained. One postulate which has been advanced in explanation of the advantageous results is that the free water droplets act as nuclei upon which the wax crystals form and in this way the actual number of nuclei formed are controlled and thereby control the size of the resultant wax crystals. Another postulate which has been proposed is that each finely divided particle of water serves as a body, upon the interface of which wax nuclei collect thereby causing a large wax agglomerate to form. In the art of filtration it is known that larger crystals or larger crystal agglomerates filter more rapidly than small crystals and thus either of the postulates advanced would result in a more rapid filtration rate. In any event the procedure of the present invention does result in substantially improved filtration rates.

We claim:

1. A method of dewaxing a waxy mineral oil including the steps of incorporating into a solution of waxy mineral oil and dewaxing solvent at a temperature above the wax nucleation temperature, a water-in-oil type of emulsion formed by admixing solvent, oil, and water in which at least 90% of the water is within the particle size range of 5 to 20 microns in an amount such that the finely dispersed water particles are present and remain in the solution in an amount within the range of 0.25 to 5% by

volume based on the solution at a wax nucleation temperature, chilling the resultant solution containing said finely dispersed water particles to a temperature substantially below the wax nucleation temperature to cause wax crystals to form while said dispersion water particles are present and subsequently separating a wax crystal fraction from a wax free oil fraction.

2. A method of dewaxing a waxy mineral oil containing wax within the range of 5 to 25% by volume including the steps of dissolving said waxy mineral oil at a temperature above the wax nucleation temperature in a solvent having a low water solubility, adding to the solution a water-in-oil type of emulsion formed by admixing solvent, oil, and water, and having the water dispersed so that at least 90% is within the particle size range of 5 to 20 microns in an amount within the range of .25 to 1.10% by volume based on the solution at a wax nucleation temperature, chilling the waxy oil solution containing said finely dispersed particles of water to a temperature substantially below the wax nucleation temperature to cause wax crystals to form in the presence of said dispersed particles of water and subsequently separating a wax crystal fraction from a wax free oil fraction.

3. A method for dewaxing a waxy mineral oil containing wax within the range of 5 to 25% by volume which includes the steps of dissolving said waxy mineral oil at a temperature above the wax nucleation temperature in propane, forming a water-in-oil type of emulsion by admixing methyl ethyl ketone, oil and water with the water dispersed so that at least 90% is within the particle size range of 5 to 20 microns, adding said emulsion to said solution of waxy oil in an amount to incorporate from .25 to 5% by volume based on the solution at wax nucleation temperature of finely dispersed water in said solution of waxy oil, chilling said waxy oil solution containing said finely dispersed water particles to a temperature substantially below the wax nucleation temperature to cause wax crystals to form in the presence of said dispersed water particles and subsequently separating a wax crystal fraction from a wax free oil fraction.

4. A method in accordance with claim 3 in which said emulsion is formed by mixing approximately 82 parts by volume of water, 18 parts by volume of methyl ethyl ketone and 300 parts by volume of oil.
